HOUSING FOR A MAILBOX OR THE LIKE

Alan W. Duncan, Itasca, and Joseph A. Burlini, Morton Grove, Ill., assignors to Sears, Roebuck and Co., Chicago, Ill., a corporation of New York

Filed Apr. 22, 1963, Ser. No. 74,546

Term of patent 14 years

(Cl. D74—9)

FIG. 1 is a perspective view of a housing for a mailbox or the like;

FIG. 2 is an elevational view of the side opposite the side facing the viewer in FIG. 1;

FIG. 3 is a front elevational view, and

FIG. 4 is a top plan view thereof.

The essential features of our design reside in the portions shown in solid lines.

We claim:

The ornamental design for a housing for a mailbox or the like, as shown and described.
